UNITED STATES PATENT OFFICE.

AUGUST KROPP, OF BRYAN, TEXAS.

KEY-RING HOLDER.

1,212,511.

Specification of Letters Patent. Patented Jan. 16, 1917.

Application filed December 8, 1915. Serial No. 65,763.

To all whom it may concern:

Be it known that I, AUGUST KROPP, a citizen of the United States, residing at Bryan, in the county of Brazos and State of Texas, have invented certain new and useful Improvements in Key-Ring Holders, of which the following is a specification.

My invention relates to an improvement in key ring holders, the object being to provide a device capable of being quickly and easily fastened to the belt or other wearing apparel of the owner, and in so doing providing a means of fastening a key ring against accidental loss or removal therefrom.

In the accompanying drawings: Figures 1 and 2 are views in side elevation showing two different adjustments of the key ring holder; and Fig. 3 is a view of the blank out of which the main part of the key ring holder is formed. Fig. 4 is a detailed view of the lever 5.

A narrow strip of moderately thin spring metal is bent in opposite directions at opposite ends to form hooks 1 and 2 and the central web 3.

A U-shaped spring 4 fits within and is secured at one end to one end of the hook 1. Lever 5 extends through a slot 6 in the center of web 3, and the two lugs 7, 7, on opposite sides of this lever are fulcrumed in the crimped recesses 8, 8, at opposite sides of the slot, and the short inner end 9 of the lever extends within the hook 1, where the free end of spring 4 bears yieldingly thereupon with sufficient pressure to hold the lever either in an open position as shown in Fig. 1 or in a closed position, shown in Fig. 2, in which latter position the pin 10 on the free end of the lever extends through the hole 11 in the end of hook 2 until it engages the central web 3 of the key ring

holder thereby simultaneously closing the opening of hook 2 and forcing the spring 4 tight against the belt or band at the upper edge of the wearer's trousers, or any other part of the wearing apparel to which the key ring is fastened.

To insure a secure fastening of the hook 1 upon the wearer's clothing, a pointed stud 12 projects inwardly from the end of hook 1 and between this and the spring 4 a portion of the garment is clamped. Thus it will be seen that the lever, which is held in its various positions by the spring, performs two functions simultaneously, to wit; it holds the device securely upon the garment and it prevents the key ring from accidental displacement therefrom.

I claim:

1. A key ring holder comprising a plate 60 bent oppositely at its ends to form two oppositely extending hooks, a spring within one hook, and a lever pivotally connected with the plate and having one end in constant engagement with the spring to positively hold it in its upper and lower positions, and the other end operating to close one of the hooks when in one of its positions.

2. A key ring holder comprising a strip of spring metal, the ends of which are bent 70 into hooks, the center of which has a slot, one hook having an inwardly extending stud and the other having a hole through its end, a spring secured within one hook with its free end between the slot and stud, and a 75 lever extending through the slot pivotally connected to the holder with one end constantly bearing upon the spring and the other end having a pin in position to pass through the hole in the end of one hook. 80

In testimony whereof I affix my signature.

AUGUST KROPP.
